4 Claims. (Cl. 179—84)

My invention relates to telephony systems and more particularly to signal receivers for such systems.

My invention is particularly concerned with signal receivers for receiving signalling currents which are transmitted directly or by carrier waves over a conductor which may also be used for speech transmission, and which currents have a frequency located in or adjacent to the frequency range of the speech currents or the speech sideband.

As is well known, signal receivers of the above type must be such that the signal circuit cannot be erroneously energized by speech currents of a frequency which is the same as or close to the frequency of the signal currents.

The main object of my invention is to provide a signal receiver with which the signal circuit can be energized only by the signal currents.

A further object is to provide a signal receiver which is simple in construction and reliable in operation.

Further objects and advantages will appear as the description progresses.

In accordance with the invention I control the signal circuit by two relays or relay combinations of which one sets the signal circuit into operation with a time-lag and the other sets the signal circuit into operation without a time-lag, and make the time-lag of such duration that the signal circuit will not be established by current pulses caused by speech currents of a frequency close to or equal to the signal current frequency.

In order that the invention may be clearly understood and readily carried into effect, I shall describe the same in more detail with reference to the accompanying drawing in which:

Figure I is a schematic diagram of a signal receiver according to one embodiment of the invention, and

Figure II is a schematic diagram of a signal receiver according to another embodiment of the invention.

The signal receiver shown in Figure I comprises a transformer 3 having a primary winding 9 whose terminals 1 and 2 are adapted to be connected to a telephony transmission line (not shown) transmitting both low-frequency signal currents and speech currents. If the signal currents are transmitted by carrier wave over a conductor, the terminals 1 and 2 would be connected to the output circuit of a demodulator which demodulates both the modulated signal currents and the speech currents received. Thus, in any case both low-frequency signal currents and speech currents are supplied to terminals 1 and 2.

Transformer 3 has a secondary winding 10 tuned to the signal frequency by a condenser 4, and having one end connected through a conductor 11 to the grid of a triode 5, which is connected as an anode rectifier, and having its other end connected through a biasing battery 12 to the cathode of tube 5.

The receiver also comprises two relays 13 and 14 having normally-open armatures 15 and 16 respectively connected in series in a signal circuit 6. Armature 15 acts instantaneously, whereas armature 16 acts with a predetermined time delay both in opening and closing. As time-delay relays of this type are well known in the art further description of the same is believed unnecessary.

The coils of relays 13 and 14 are connected in parallel in the plate circuit of tube 5 and for this purpose one end of each coil is connected through a conductor 17 to the plate of tube 5, and the other ends of the coils are connected together and through a battery 7 and a conductor 18 to the cathode of tube 5, a condenser 8 connected across the plate and cathode of tube 5 serve to smooth the rectified plate current.

In operation of the receiver, the signal currents received at terminals 1 and 2 produce a rectified voltage across the coils of both relays 13 and 14. Relay 13 is energized and armature 15 closes its contact practically instantaneously but relay 14 becomes energized and armature 16 closes its contact only after a predetermined time interval. Thus, the signal circuit 6 is established only at a predetermined time after voltage is applied to the coils of relays 13 and 14.

When the speech currents received contain components whose frequencies are located adjacent the signal frequency and produce a voltage at the grid of tube 5 for a short time, the rectified voltage applied across the coils of relays 13 and 14 causes armature 15 to close immediately whereas armature 16 remains open for a short time period. As those components of the speech currents whose frequencies are located adjacent the signal frequency occur for only a short time interval, armature 16 will not be closed by such currents, provided, of course, the time-lag in relay 14 is made longer than the duration of such currents. In practice, the relay 14 may have a time-lag of about $\frac{1}{5}$ — $\frac{1}{10}$ second. When signal currents consisting of successive impulses are received the relay 13 opens and closes its armature 15 in the rhythm of these impulses, the armature 16 of the relay 14 remains, however, closed due to the time-lag of about $\frac{1}{5}$ — $\frac{1}{10}$ second which is longer than the duration of each interval between two suc-

sive signal impulses. By the closing and opening of the armature 15 of relay 13 the signal impulses are transmitted in the signal circuit 6.

The receiver shown in Figure 2 is similar in many respects to that of Figure 1 and the same reference numerals are used to designate the same parts. However, in Figure 2 the relay 14 of Figure 1, which relay is energized and de-energized with a time-lag, is replaced by two relays 20 and 22 having normally-closed armatures 21 and 23 respectively, both of the latter relays being energized quickly but de-energized with a time-lag. The coil of relay 20 is connected in parallel with the coil of relay 13, whereas armature 21 controls a circuit comprising the coil of relay 22 and a battery 24. Armature 23 is connected in series with armature 15 in the signal circuit 6.

When signal currents are received at terminals 1 and 2, rectified voltage is applied across the coils of relays 15 and 20 with the result that the armature 15 closes immediately and armature 21 immediately opens and causes deenergization of relay 22. After a suitable time interval armature 23 closes to thereby establish the signal circuit 6.

If the signal currents are constituted by a number of periodical pulses, armature 15 of relay 13 will open and close periodically so that these pulses are transmitted in the signal circuit 6. Although the energization of relay 20 is periodically interrupted by these pulses, this relay is de-energized with a time-lag, and thus the armature 21 will remain open, relay 22 will remain de-energized and armature 23 will remain closed.

When receiving speech-current components of short duration armature 21 is also opened, but due to the fact that relay 22 is de-energized with a time-lag, armature 23 is prevented from closing and thus the signal circuit 6 will not be erroneously established by these speech currents.

The signal receiver as shown in Fig. 2 has the advantage over that shown in Fig. 1, that the relay combination 20 and 22 contains relays which are only de-energized with a time-lag i. e. have a time delay in only one direction. Such relays are more readily constructed than a relay such as the relay 14 of Figure 1 which has to be energized as well as de-energized with a time-lag.

I wish it to be understood that I do not desire to be limited to the exact details of construction shown and discussed or to the use of time relays of any particular type, because obvious modifications will occur to a person skilled in the art.

What I claim is:

1. In a telephony system in which signal currents of a frequency at least close to the frequency range of the speech-currents or the speech side-band are transmitted over a conductor adapted to serve also for speech transmission, a local signal circuit, a signal receiver controlling said local signal circuit and comprising electro-responsive means including a contact connected

in said circuit and adapted to close and open without time delays, second electro-responsive means including a contact connected in said circuit and adapted to close and open with predetermined time delays, and means to simultaneously energize both said means with a voltage produced by the signal currents and speech currents of similar frequency.

2. In a telephony system in which signal currents of a frequency at least close to the frequency range of the speech-currents or the speech side-band are transmitted over a conductor adapted to serve also for speech transmission, a local signal circuit, a signal receiver controlling said local signal circuit and comprising an electro-magnetic relay having a contact connected in said circuit and adapted to close and open without a time delay, a second electro-magnetic relay having a contact connected in said circuit and adapted to close and open with predetermined time delays, and means to simultaneously energize both relays with voltage pulses produced by the signal currents and speech currents of similar frequency.

3. In a telephony system in which signal currents of a frequency at least close to the frequency range of the speech-currents or the speech side-band are transmitted over a conductor adapted to serve also for speech transmission, a local signal circuit, a signal receiver controlling said local signal circuit and comprising an electrical relay having a contact connected in said circuit and adapted to close and open without a time delay, a second electrical relay having a normally-closed contact adapted to open with a time delay, a circuit including said latter contact and a voltage supply, a third electrical relay having a coil in said latter circuit and a normally-open contact in said signal circuit and adapted to open with a time delay, and means to simultaneously energize the first two relays with voltage pulses produced by the signal currents and speech currents of similar frequency.

4. In a telephony system in which signal currents of a frequency at least close to the frequency range of the speech-currents or the speech side-band are transmitted over a conductor adapted to serve also for speech transmission, a local signal circuit, a signal receiver controlling said local signal circuit and comprising an electrical relay having a normally-open contact connected in said circuit and adapted to close and open without a time delay, a second electrical relay having a normally-open contact connected in said circuit and adapted to both close and open with predetermined time delays, and means to simultaneously energize both said relays with a voltage produced by the signal currents and by speech currents of similar frequency.

WILLEM SIX.
